UNITED STATES PATENT OFFICE

FRANK C. BRADBURY, DECEASED, LATE OF RIVERSIDE, ILLINOIS, BY CARRIE LANDON
BRADBURY, EXECUTRIX, OF RIVERSIDE, ILLINOIS, ASSIGNOR TO CRANE CO., OF
CHICAGO, ILLINOIS, A CORPORATION OF ILLINOIS

WATER JACKETED SMOKE HOOD

Application filed December 29, 1928. Serial No. 329,241.

This invention pertains to smoke hoods or smoke boxes, as they are variously known, and which form a part of or are adapted to be connected to boilers or heaters of different types although more particularly adapted to be used in connection with hot air, hot water or steam boilers for domestic uses.

One of the primary objects of the invention is to provide a smoke hood or smoke box so constructed and arranged that it may be interchangeably connected to the same or different boilers with reference to installation on top or on the side of the boiler depending upon the construction of the boiler, the head room provided, etc.

It is also an object of the invention to provide a jacketed smoke hood in which the heat of a deflected flow of the flue gases is utilized.

Other objects, as well as the advantages and uses of the invention, will be or should become readily appreciated and understood after reading the following description and claim and after viewing the drawings in which:

Fig. 1 is a side elevational view of one type of domestic boiler illustrating the attachment of the invention in either of two positions,

Fig. 2 is a perspective view of a top portion of a different type of boiler showing the invention applied thereto in one position,

Fig. 3 is a top plan detail view of a preferred form of the invention,

Fig. 4 is a side elevational view thereof, and

Fig. 5 is an elevational view of the outer end thereof.

The smoke hood or smoke box is preferably an iron casting although it may be made of other materials and in other ways as will be appreciated. In Figs. 1 and 2 it is designated 1 as a whole and may be attached either to the top of a boiler or to one side of a suitable outlet opening for products of combustion as illustrated in these figures. The hood at the top is provided with a circular opening at its place of attachment to the boiler while that at the side is formed as shown in detail in Figs. 3, 4 and 5 except as will be pointed out hereinafter.

Referring more particularly to Figs. 3, 4 and 5 a casing or shell 2, of substantially elliptical or oval shape at its end to be disposed against the boiler and open at such end for a connection over a similarly shaped opening in the boiler top or side wall, tapers down and merges with a cylindrical wall 3 which is extended and somewhat reduced as shown at 4 to provide one of a pair of stack pipe connections. The other stack pipe connection designated 5 has a generally cylindrical wall 6 which merges with the wall 2 as shown at 7, the opening being in a plane non-parallel to either opening 4 or the inlet opening to the hood. In these figures the end of the hood that is to be disposed against the boiler is plane but where the hood is to be attached to a curved surface as in the horizontal position of Fig. 1, this end will be curved to correspond to such surface, suitable clearance being left for the damper, as will be understood.

Surrounding practically all of the wall 2 is a water chamber 8 provided by a second casing or shell 9 preferably integral with the casing or shell 2 but spaced therefrom. If the smoke hood is made as a casting this chamber is cored out as will be understood. The chamber 8 is extended and surrounds or embraces a greater part of each of the stack connections 4 and 5 as shown at 11 being formed by shells or casings 12 and 13 spaced from the walls 3 and 6 respectively, and merging with the shell or casing 9. This provides a water jacket surrounding a greater proportion of the smoke hood including what may be termed the body portion formed by the shell 2 and what may be termed the stack portions formed by the walls or shells 3 and 6. Heated gases and other products of combustion passing through the smoke hood or smoke box into a stack usually carry a great many more heat units than necessary to provide proper draft facilities and these extra heat units are absorbed by water contained in the jacket or water chamber surrounding the body and stack portions of the hood. Suitable connection bosses 14 and 15 providing inlet and outlet openings 16 and 17 respectively.

tively for connection of water inlet and outlet pipes are provided on the walls of the outer shell or casing, the inlet opening preferably being that designated 17 and the outlet opening preferably being that designated 16. Heated water from the smoke hood may supply a radiator or a water service outlet pipe for any purpose.

The smoke hood is provided with suitable external lugs 18 which are drilled or otherwise arranged for the reception of bolts or the like whereby the hood may be secured to the boiler and internally of each stack connection pairs of bosses 19 are provided for connection of bolts or the like for securing a stack pipe or a cap closure as the case may be. Parallel its long axis and adjacent its boiler connection end the body portion of the smoke hood is provided with bosses 21 and 22 the first of which is drilled through as shown at 23 and the latter of which is provided with an internal socket 24 for the reception of trunnions 25 and 26 respectively of a damper 27. The trunnion 25 is provided with a damper control lever 28 having a handle 29, the trunnion 25 being pinned in a socket 31 formed in the damper. The boss 21 is provided with projections 32 forming stops between which a projection 33 on the lever 28 may move and be limited. Between the stack connections 4 and 5 an opening 34 is provided to permit the smoke hood or smoke box to be cleaned out or to permit inspection or to reduce the draft through the boiler etc. This opening is adapted to be closed by a door, not shown, but normally hinged at its upper edge to a hinge plate or door frame secured by bolts passing through drilled apertures 35.

It will now be apparent that the smoke hood is interchangeable with the top, side or back of a boiler or furnace and may be connected to a horizontal or vertical smoke stack in either of such positions. It is preferable to use a stack connection which does not lie in a plane parallel to the hood inlet in order to cause the hot gases of combustion to be deflected and of course, the stack connection opening of the hood which is not being used will be closed by a suitable cap or plug, not shown. Water entering the inlet through the water chamber in the hood enters at the theoretically coolest place, flows upwardly or downwardly as the case may be about the combustion channel through the smoke hood and passes out at the theoretically hottest portion namely adjacent the boiler, from whence it flows to wherever it may be desired for use. This arrangement effects considerable saving and unnecessary heat losses and provides a quick mode of obtaining hot water. There are many other advantages resident in the invention with which it does not seem necessary to burden this description.

While the preferred form of the invention has been illustrated and described it is susceptible of many changes and variations bearing little, if any, structural resemblance to such preferred form. Consequently it is not desired that this application be limited except by the spirit of the invention and the scope of the appended claim.

What is claimed is:

A combined smoke hood and economizer comprising an integral casing providing a channel for the products of combustion of a furnace and having a body portion provided with an inlet and a stack portion having a plurality of outlet openings for the products of combustion adapted to be selectively connected either to horizontal or vertical stove pipes, said casing including means thereon for securing the inlet of said casing directly to the smoke offtake of a furnace, one of said stack openings lying in a plane parallel to said inlet and the other lying in a plane at right angles thereto, said channel through said latter outlet being tortuous whereby the products of combustion are caused to be deflected in passing therethrough, an outer casing surrounding said first mentioned casing between said inlet and outlets and embracing a part of said body portion and a part of said stack portion and providing a water chamber therebetween in direct contact with that portion of the casing which deflects the products of combustion, and means for connecting said chamber to water inlet and outlet pipes.

In witness of the foregoing I affix my signature.

CARRIE LANDON BRADBURY,
Executrix of the Estate of Frank C. Bradbury, Deceased.
